(57) CLAIM

I claim the ornamental design for a sexual stimulator, as shown and described.

DESCRIPTION

FIG. 1 is a front side perspective of a sexual stimulator showing the design;

FIG. 2 is a top plan view thereof;

FIG. 3 front elevational view thereof;

FIG. 4 is a right side elevational view thereof;

FIG. 5 is a left side elevational view thereof;

FIG. 6 is a rear elevational view thereof; and,

FIG. 7 is a bottom plan view thereof.

The broken lines shown in FIGS. 1,2,3,4,5,6, and 7 are for illustrative purposes only and form no part of the claimed design.
